UNITED STATES PATENT OFFICE.

EDWIN F. GUTH, OF ST. LOUIS, MISSOURI.

ELECTRIC-LIGHTING SOCKET.

Application filed December 6, 1927, Serial No. 238,104. Renewed June 15, 1929.

My invention relates to the kind of sockets disclosed in my copending application, Serial No. 184,873, although it may be found useful in other sockets which are constructed of electrical insulating material.

My invention has for its object, the provision of a cap for such sockets, which will provide for the connection of wires which come to the fixture through the central nipple or hollow stud of an outlet box, or it is equally available when it is desirable to spread or divide the wires, where they are not led in through the central nipple or hollow stud of said outlet box, or where the wires are led to the socket through a fixture stem.

My invention has for its further object, to provide means which will insure the cap always registering with the openings in the socket through which are passed the supporting screws, so that, regardless of the action of the workman in turning the socket around when the cap is disconnected, it will be automatically brought into position so the screws will be in register to enter the threaded openings prepared in the cap for their reception. This serves to materially decrease the labor in assembling, and hence is most desirable.

By means of accomplishing the foregoing objects may be more readily understood by having reference to the accompanying drawings, which are hereunto annexed and made a part of this specification, in which—

Fig. 1 is a side elevation of a socket equipped with my improved cap;

Fig. 2 is a similar view, showing connections for a different form of wiring;

Fig. 3, is a top or plan view of my improved cap;

Fig. 4 is a vertical sectional view, taken on the line 4—4 in Fig. 3; and

Fig. 5 is a side elevation of the socket, showing the means for insuring registering of the cap with the supporting screws.

Similar reference numerals refer to similar parts throughout the entire description.

As shown in the drawings, my improved socket 1 is formed of insulating material, and is provided with the standard threaded receptacle 2 for the electric lamp bulb. The socket 1 has a cap 3 secured to its upper end 4, by means of two screws 5 and 6, mounted

in openings 7 and 8 formed in the socket 1. The screws 5 and 6 are screwed into threaded openings 9 and 10 formed in the cap 3. This cap 3 is formed with a central neck 11 having internal threads, and is adapted to be screwed on to the central stud 12 of the outlet box 13. Two peripheral notches, 14 and 15, are cut in the cap 3, the sides of which fit the upstanding lugs 16 and 17 formed in the top of the socket 1. These notches 14 and 15 are made deep enough to leave a space 30 intermediate the inner surface of the lugs 16 and 17 and the back of the notches 14 and 15, so as to permit the wires 23 and 24 to be led through the space 30 when the outlet wires do not come through the central stud 12. The lugs 16 and 17 serve to insure the holes 9 and 10 always registering with the screws 5 and 6 whenever the cap 3 is placed so that the peripheral notches 14 and 15 straddle the lugs 16 and 17. Intermediate the cap 3 and the socket 1, I place a sheet of insulating material 18. This is cut at 19 and 20 so as to provide ears 21 and 22 which can be upturned, as clearly shown in Figs. 1 and 2. In this manner I accomplish a double result: I shield the wires 23 and 24 from the edge 25 of the cap 3, thus preventing the chafing of the insulation; and I also provide additional insulation for the cap 3, so that even if the wire were bare it would not cause a short. As I form the central neck 11 hollow, it follows that when the wires 23 and 24 are to be connected through the stud 12 of the outlet box 13 they can be led in as shown in Fig. 1.

Having described my invention, what I regard as new, and desire to secure by Letters Patent of the United States, is:

1. In a device of the character described, an electric socket of insulating material, upwardly extending peripheral lugs on its top, a metal cap, a central neck thereon which is internally threaded, said cap having peripheral notches therein, the sides of which engage said lugs, there being a space between the inner surface of each of said lugs and the end of its notch, screws mounted in said socket which engage screw-threaded openings in said cap, a layer of insulating material intermediate said cap and said socket, and ears thereon which extend upwardly through said spaces;

2. In a device of the character described, an electric socket of insulating material, upwardly extending peripheral lugs on its top, a metal cap, a central neck thereon which is internally threaded, said cap having peripheral notches therein, the sides of which engage said lugs, there being a space between

the inner surface of each of said lugs and the end of its notch, screws mounted in said socket which engage screw-threaded openings in said cap, and means to insulate the bases of said notches. 10

EDWIN F. GUTH.
